STRIPPING ELECTRODEPOSITED METAL SHEETS

Charles E. Yates, Perth Amboy, N. J., assignor to
Anaconda Copper Mining Company, a corpora-
tion of Montana

Application June 22, 1940, Serial No. 341,889

7 Claims. (Cl. 204—13)

This invention relates to stripping electrodeposited metal sheets from rotating cathodes, and provides an improved method and apparatus for continuously stripping such sheets. The invention is particularly adapted for use in stripping thin sheet copper from rotating cathodes, but is applicable to the continuous stripping of any electrodeposited metal.

A successful process for continuously producing thin sheet metal electrolytically has been in use for some time and has enabled the production of very thin sheet metal in greater widths than can be produced by other means. This process, as carried out for the manufacture of thin sheet copper, for example, involves depositing the copper electrolytically on the cylindrical surface of a rotating cathode drum which is partially immersed in a suitable electrolyte. As the cathode rotates above the surface of the electrolyte, the copper deposited on the cathode surface is stripped therefrom and is passed around a take-up roll. The copper sheet may be wound on the take-up roll or may be wound on a separate roll to which the copper sheet is passed from the take-up roll. The width of the sheet copper product is determined by the width of the cathode face of the drum, and thickness of the sheet is governed by the speed at which the drum rotates. At relatively low speeds each unit of area of the cathode is immersed in the electrolyte for a relatively long period of time per revolution of the drum, and in consequence a relatively thick deposit is formed on the drum and a relatively thick sheet product is obtained. At higher speeds each unit of area of the cathode is immersed in the electrolyte for a relatively short period of time per revolution of the drum and only a relatively thin deposit of copper is formed thereon with the resulting production of a thin copper sheet. Sheet copper weighing as little as $\frac{1}{8}$ of an ounce per square foot (corresponding to a thickness of 0.00017 inch) and even less may be made by this process, and thicker sheets are readily produced.

Copper sheets weighing about one ounce per square foot and upwards (upwards of about 0.00135 inch in thickness) may be stripped from the rotating cathode without particular difficulty, for example by passing the sheet from the cathode over a cylindrical stripping roll or bar. With thinner sheets, however, stripping is very difficult because of the ease with which the sheets tear at the edges, and a cylindrical stripping roll or bar is not satisfactory for stripping these thinner sheets from the rotating cathode. In pro-

5 ducing such thin sheets, the varying degrees of adhesion of different local areas of the sheet to the cathode causes the stripped sheet, at the relatively high speed with which it is passed over a take-up or ironing roll for winding, to whip as it is stripped from the drum. This whipping action of relatively thin sheet copper results in uneven distribution of the stripping strain imposed on the sheet being stripped from the rotating cathode and further produces wrinkles in the thin copper sheet. The unequal distribution of stripping strain across the width of such thin sheet copper tends to tear or rip this fragile sheet. A tear not only spoils the product but causes serious delays in production. The formation of wrinkles in the product detracts from the appearance, and in some instances the utility, of such thin sheet copper and makes it difficult to wind the sheet compactly and smoothly on a roll.

10 15 20 25 30 35 40 45 50 55

Because of such difficulties as those noted hereinabove in stripping very thin electrodeposited sheet copper, special means and great care have been required heretofore in the production of long lengths of copper sheet weighing less than about one ounce per square foot.

The present invention provides an improved method for continuously stripping a thin sheet of electrodeposited metal from a rotating cathode which enables production of long lengths of such very thin sheet metal without tearing the sheet and without the formation of wrinkles therein. My new method of stripping involves maintaining the stripped sheet substantially flat and wrinkle-free as it is removed and withdrawn from the cathode, whereby the stripping strain imposed on the sheet is distributed uniformly across the width thereof. The stripped sheet is maintained substantially flat and wrinkle-free by subjecting it to a spreading operation acting from the central portion of the sheet outwardly toward the edges thereof in such a manner that local areas of relatively high stripping strain are minimized. The development of tears is thereby minimized and a substantially wrinkle-free sheet is obtained which may be wound compactly in the form of a roll.

Suitable apparatus for carrying out the new method of my invention comprises a take-up roll for the stripped sheet mounted for rotation about its longitudinal axis with said axis arranged substantially parallel to the axis of rotation of a rotating cathode drum, and means for spreading the sheet uniformly on the take-up roll. The spreading means comprises spreading elements pressing against the surface of the sheet on the

take-up roll in frictional engagement with the sheet in such manner as to spread the sheet uniformly outwardly from the central portion of the sheet toward the edges thereof. The take-up roll may serve as the winding roll or a separate winding roll may be provided to receive the spread sheet as it passes from the take-up roll.

A preferred embodiment of my invention is described hereinafter in detail with particular reference to the stripping of thin sheet copper. In the following description reference is made to the accompanying drawings in which

Fig. 1 is a diagrammatic cross-section through apparatus for producing sheet copper electrolytically, in which stripping apparatus in accordance with the invention is embodied;

Fig. 2 is a fragmentary diagrammatic cross-section through a modified form of apparatus in which the invention is embodied;

Fig. 3 is a side view taken along line 3—3 of 20 the apparatus shown in Fig. 1 and embodying the invention;

Fig. 4 is a plan view of the apparatus shown in Fig. 3;

Fig. 5 is an end view showing details of the 25 spreading elements shown in Fig. 1; and

Fig. 6 is a detailed side view of the spreading elements shown in Fig. 1.

The apparatus shown in the drawings comprises a tank 10 containing a suitable electrolyte, such for example as an acid copper sulphate solution. A cathode drum 11, which is partially immersed in the electrolyte, is mounted for rotation about its axis on a shaft 12 carried in a bearing 13. Anodes 14 curved to conform with the cylindrical cathode surface of the drum 11 are mounted in the tank 10 below the surface of the electrolyte in fixed spaced relationship with the drum. Suitable electrical connections are made to the cathode drum and to the anodes for the purpose of causing copper in solution in the electrolyte to deposit on the drum.

The cathode surface of the drum 11 is preferably of antimonial lead. The drum 11 is rotated in the direction of the arrow by means of a pulley 15 mounted on the shaft 12, and as the drum 11 rotates copper is deposited upon the portion thereof below the surface of the electrolyte. The deposited copper is lifted in the form of a sheet from the exposed cathode surface of the drum upon rotation of the drum above the surface of the electrolyte. The stripped copper sheet 16 is passed over a take-up roll 17 (as shown in Fig. 1) mounted for rotation on a shaft 18. The copper sheet is wound upon a winding reel 20 mounted for rotation about shaft 21 driven by a wheel 22 in such a manner as to maintain the proper winding tension required to strip the sheet from the rotating cathode drum.

The take-up roll 17 and the winding roll 20 (Figs. 3 and 4) preferably are of a length approximately equal to the width of the copper sheet 16 stripped from the rotating cathode. The winding roll is supported adjacent the ends of shaft 21 by brackets 23 mounted on the frame 24, each bracket being provided with a cut-away portion 25 of sufficient width to permit entry of the shaft 21 of the winding roll and to permit insertion or withdrawal of the shaft of a winding roll from the brackets when a fresh winding roll is to be substituted for a fully wound winding roll. The position of the winding roll is such that its axis (shaft 21) is substantially parallel to the cathode drum axis of rotation (shaft 12).

The spreading units are positioned with ad-

vantage directly above the take-up roll 17. The two spreading units are substantially identical, each comprising an endless conveyor such as the sprocket chain 26 mounted on sprocket wheels 27 and 28. The sprocket wheel 27 of each unit adjacent the frame 24 is mounted for rotation on a shaft 29 with the sprocket wheel 27 positioned at one end of the shaft and with a bevel gear 30 mounted on the other end of the shaft 29. These outermost sprocket wheels 27 are driven by means of bevel gears 31 engaging bevel gears 30 and mounted on a drive shaft 32 to which driving power is delivered through the driving wheel 33. The drive shaft 32 is mounted adjacent each end thereof in a cylindrical bearing section 34 which is supported from the horizontal section of frame 24 by means of the supporting member 35 mounted on the frame.

The drive shaft 32 is provided with a cylindrical sleeve 36 extending between, but out of contact with, the bevel gears 31. Brackets 37 secured to sleeve 36 near the opposite ends thereof are also secured to cylindrical bearing sections 38 in which the sprocket wheel shafts 29 are mounted. The innermost sprocket wheel 28 of each spreading unit, these wheels being positioned near the mid-point between the frames 24, are mounted on shafts 40 which are supported for free rotation within cylindrical bearing members 41. The bearing members 41 are secured, as by welding at 42, on the drive shaft sleeve 36. Thus, it will be seen that each of the sprocket wheels 27 and 28 is mounted on a shaft which is supported by a cylindrical bearing member (38 and 41, respectively) which is, in turn, secured, at its end opposite the sprocket wheels, to the sleeve 36. In accordance with this construction, the outermost sprocket wheels 27 are driven by power transmitted through the drive shaft 32 and the bevel gears 30 and 31, and all of the sprocket wheels 27 and 28, with the endless conveyor mounted thereon, are pivotally mounted or hinged about the shaft 32 by means of the sleeve 36. In this manner the spreading units are capable of substantially free movement pivotally in an arc described about the drive shaft 32.

The spreading elements which are mounted on the endless conveyor (sprocket chain 26) of each spreading unit comprise sections of soft rubber tubing 43. As shown in Figs. 5 and 6, each rubber tube section 43 is mounted on the sprocket chain 26 by means of brackets 44 connected integrally into the sprocket chain with each of the brackets being provided with a flange 45 and with the brackets held in transverse spaced relationship in the sprocket chain by means of the spacing elements 46. The rubber tube 43 is secured to the flanges 45 by suitable means such as bolts 47.

A different type of spreading element may be used, however. For example, rubber wheels, or the like, supported in caster mountings may be substituted for the rubber tubes 43. The caster mountings permit the wheel to travel transversely across the moving metal sheet without scratching or rubbing the surface of the sheet, spreading action being obtained by providing the wheels with a controlled braking action. The caster-type mounting for the wheels is not necessary but permits the spreading wheels to adjust themselves to variations in the relative speeds of their transverse movement and the longitudinal or forward movement of the metal sheet so that the wheels spread the sheet, without scratching the sheet, by their braked rolling in a direction

determined by the components of their speed transversely and longitudinally of the sheet.

The take-up roll 17 is held in fixed spaced relationship with the spreading units by means of the depending brackets 48 which are secured, as by welding or other suitable means, to the bearing members 38. The brackets 48 are provided at their extremities, directly below the outermost sprocket wheels 27 of the spreading units, with cylindrical bearing sections 50 for mounting the shaft 18 of the take-up roll 17 in suitable bearings.

The spreading unit drive shaft 32 and the take-up roll 20 are driven by means of an endless belt or a sprocket chain 51 which passes from a suitable power source around the drive wheel 22 of the winding roll, around the drive wheel 33 mounted on the spreading unit drive shaft 32, thence around an idling wheel 52 mounted on the frame 24 for rotation about an axis substantially parallel to the axis of rotation of the winding roll 20 and the driving wheel 33.

The take-up roll may comprise the winding roll 20 as shown in the modification of my apparatus illustrated in Fig. 2. In this modification the winding roll 20 is supported by the bracket 23 and is mounted for rotation about an axis (shaft 21) substantially parallel with the axis of rotation of the cathode drum 11 and is positioned directly below the spreading units.

The spreading elements 43 press against the surface of the copper sheet on the take-up roll in such manner as to spread the sheet uniformly outwardly from the central portion of the sheet toward the edges of the sheet. This spreading operation is effected by maintaining the spreading elements 43 in frictional engagement with the stripped copper sheet in contact with the take-up roll with the spreading elements of each of the two spreading units moving outwardly from the central portion of the sheet toward the edges of the sheet in the direction of the arrows shown in Fig. 3.

The speed of the spreading elements 43 in frictional contact with the stripped copper sheet may be maintained with particular advantage about fifteen times as great as the forward movement of the stripped sheet from the rotating cathode drum 11 toward and around the take-up roll 17. However, lesser or greater relative speeds between the lateral movement of the spreading elements and the longitudinal or forward movement of the stripped copper sheet may be used with advantage, the relative speed of 15:1 referred to above being particularly desirable and effective in the stripping of very thin copper sheet weighing about $\frac{1}{3}$ of an ounce, or less, per square foot (thicknesses of about 0.0004 inch or less).

In the apparatus shown in Figs. 1, 3 and 4, the spreading units and the take-up roll 17 are maintained in fixed spaced relationship to one another. However, both of these elements are capable of pivotal movement on the sleeve 36 in an arc struck from this sleeve so that take-up roll 17 is supported on the surface of the metal sheet wound on the winding roll 20, and yet is free to move vertically with variations in the thickness of the roll of metal sheet as the sheet is being wound on the winding roll.

In the modification of my novel apparatus shown in Fig. 2 wherein the winding roll 20 serves the function of a take-up roll, the spreading units are also free to move pivotally about the sleeve on drive shaft 32. In this manner, uni-

form pressure for frictional engagement is maintained between the spreading elements and the metal sheet on the take-up roll (winding roll 20) by the constant weight of the spreading units which are free to move vertically with variations in the thickness of the winding roll as the metal sheet is wound thereon.

When commencing production of copper sheet, a relatively thick deposit of copper is formed on the cathode surface of the drum. A thick deposit may be stripped initially by hand without much trouble. The free end of the sheet thus stripped is passed over the take-up roll 17 and is secured to the winding roll 20 as shown in Fig. 1, or the free end of the sheet may be passed over and secured to the winding roll 20 when the winding roll is employed as the take-up roll as shown in Fig. 2. Thenceforward the entire operation may be automatic.

By means of the stripping method and apparatus provided by this invention it is possible continuously to strip long lengths of very light weight electrodeposited sheet metal such as sheet copper weighing $\frac{1}{3}$ of an ounce per square foot and less. My new stripping method and apparatus uniformly distributes the stripping strain across the width of such thin metal sheet whereby local areas of relatively high strain are minimized with the resulting substantial elimination of tears in the stripped metal sheet resulting from uneven distribution of stripping strain across the width of the sheet. Furthermore, the new stripping method and apparatus of my invention facilitate the winding of thin electrodeposited metal sheet on a winding roll by eliminating wrinkles which form when an uneven stripping strain is applied to the sheet and, accordingly, make it possible to produce smoothly wound rolls of very thin sheet metal. My new stripping method and apparatus, by uniformly distributing the stripping strain imposed on the thin metal sheet, enable the use of substantially higher stripping tension than could be used heretofore with resulting improvements in the stripping of such thin metal sheet from a rotating cathode drum.

I claim:

1. The method of continuously stripping a thin sheet of electrodeposited metal from a rotating cathode with production of long lengths of such thin sheet without tearing thereof which comprises winding the sheet on a roll under such tension as to strip the sheet from the cathode, and subjecting the stripped sheet while substantially flat and under said stripping tension to a spreading operation in such manner that the stripping tension is distributed uniformly across the width of the sheet in such a manner that local areas of relatively high stripping strain are eliminated and that a substantially wrinkle-free sheet is obtained.

2. Apparatus for continuously stripping a thin sheet of electrodeposited metal from a rotating cathode drum comprising a take-up roll for the sheet mounted for rotation about its longitudinal axis with said axis arranged substantially parallel to the drum axis of rotation, and spreading elements pressing against the surface of the sheet on the take-up roll in such manner as to spread the sheet uniformly outwardly from the central portion of the sheet toward the edges of the sheet.

3. Apparatus for continuously stripping a thin sheet of electrodeposited metal from a rotating cathode drum with production of long lengths

of such thin sheet without tearing thereof comprising spreading elements frictionally engaging the stripped sheet in such manner as to spread the sheet uniformly outwardly from the central portion of the sheet toward the edges of the sheet and to distribute stripping tension on the stripped sheet uniformly across the width of the sheet in such manner that local areas of relatively high stripping strain are eliminated, and a winding roll mounted for rotation about its longitudinal axis for winding the stripped and spread sheet in the form of a roll, said spreading means being located between the cathode drum and the winding roll.

4. Apparatus for continuously stripping a thin sheet of electrodeposited metal from a rotating cathode drum comprising a take-up roll for the sheet mounted for rotation about its longitudinal axis with said axis arranged substantially parallel to the drum axis of rotation, and spreading elements frictionally engaging the sheet on the take-up roll and arranged to move in frictional contact with the sheet from the central portion thereof outwardly toward the edges of the sheet.

5. Apparatus for continuously stripping a thin sheet of electrodeposited metal from a rotating cathode drum comprising a take-up roll for the sheet mounted for rotation about its longitudinal axis with said axis arranged substantially parallel to the drum axis of rotation, two spreading units each having a plurality of spreading elements mounted on an endless conveyor in such manner that at all times at least one spreading element of each unit is in position to engage frictionally a sheet on the take-up roll, and means for driving the conveyor in each unit in opposite directions in such manner that the spreading elements of each unit in position for frictional engagement with the sheet move

in a direction substantially perpendicular to the direction of movement of the sheet and from the central portion of the sheet outwardly toward the opposite edges thereof.

6. Apparatus for continuously stripping a thin sheet of electrodeposited metal from a rotating cathode drum comprising a frame, a winding roll for the sheet mounted on the frame for rotation about its longitudinal axis, a shaft mounted on the frame substantially parallel to the longitudinal axis of the winding roll, a take-up roll for receiving the sheet from the cathode drum and for passing the sheet to the winding roll, the take-up roll bearing upon the surface 15 of the sheet wound on the winding roll and being mounted for rotation about an axis substantially parallel to the longitudinal axis of the winding roll, means for permitting pivotal movement of the take-up roll in an arc about the 20 shaft, and spreading elements in fixed relationship with the take-up roll and frictionally engaging the sheet in contact with the take-up roll.

7. Apparatus for continuously stripping a thin sheet of electrodeposited metal from a rotating cathode drum comprising a frame, a winding roll on which the sheet is wound, said roll being mounted on the frame for rotation about its longitudinal axis, means for rotating the roll 30 in such manner as to pull the sheet from the cathode drum, a shaft mounted on the frame substantially parallel to the longitudinal axis of the winding roll, spreading elements bearing upon the sheet being wound on the roll and 35 adapted to move in frictional contact with the sheet from the central portion of the sheet outwardly toward the edges thereof, and means for permitting pivotal movement of the spreading elements in an arc about the shaft.

CHARLES E. YATES.
